DESIGN FOR A DRESS

Ada Dallanegra, Woodside, Long Island, N. Y.

Application December 21, 1937, Serial No. 73,775

Term of patent 3½ years

To all whom it may concern:

Be it known that I, Ada Dallanegra, a citizen of the United States, residing at 42-17 64th Street, Woodside, Long Island, in the county of Queens, city and State of New York, have invented a new, original, and ornamental Design for a Dress, of which the following is a specification, reference being had to the accompanying drawing, constituting a part thereof.

Fig. 1 is a front view of the dress.

Fig. 2 is the rear view of the dress as shown in Fig. 1.

The characteristic feature of my design resides in the combination on the specific dress disclosed of the contrastingly colored edging around the stand-up collar and on the short sleeves in association with the leaf-like ornamentation below the collar and the high rounded waist-yoke with gathered fullness extending into the buttoned blouse front, as shown.

I claim:

The ornamental design for a dress substantially as shown and described.

ADA DALLANEGRA.
